UNITED STATES PATENT OFFICE.

WILLIAM S. BRELSFOARD, OF HENO, OHIO.

BRIDGE.

SPECIFICATION forming part of Letters Patent No. 624,618, dated May 9, 1899.

Application filed October 3, 1898. Serial No. 692,537. (No model.)

To all whom it may concern:

Be it known that I, WILLIAM S. BRELSFOARD, a citizen of the United States, and a resident of Heno, in the county of Butler and 5 State of Ohio, have invented certain new and useful Improvements in Bridges, of which the following is a specification.

My invention relates to that class of bridges wherein the roadway is adjustably supported 10 between side trusses; and the objects of my improvement are embodied in the construction of the arches and the imposts and the adjustable manner in which the beams that form the arches are connected together and 15 with the imposts. These objects are obtained in the following-described manner, as illustrated in the accompanying drawings, in which—

Figure 1 is a side elevation of the bridge; 20 Fig. 2, a perspective view of an impost; Fig. 3, the manner of connecting the stringers, &c., to the post; Fig. 4, a sectional elevation, and Fig. 5 a plan, of one of the angles of the arch.

25 In the drawings, 6 represents the springer-beams, and 7 the key-beam, of the arch. Metal imposts 8 are mounted on the abutments and are each formed with a transverse concave seat 9, that contains groove 10 across the middle portion of the face, a middle longitudinal opening 11, a transverse bolt-hole 12, a lug 13 on the front projection of its base, and socket 14 in the middle of its top surface. Supporting-posts 15 depend from the angles 30 of the arch and each consists of two pieces of channel-iron connected together at their edges by lattice-work or bridging. (Not shown.) Yokes 16, secured to said posts by bolts 17, support the ends of floor-beams 18. Joists 19 rest with their extremities on the floor-beams and on the abutments 20 to support the flooring-boards 21, placed transversely thereon to form the roadway.

Stringers 22 are articulated to bolts 17. The 45 stringers are used double in the middle span and single in the end spans that they may be inserted through respective openings 11 in the imposts and receive the threaded nuts 23, whereby they may be adjusted more or less 50 in length to determine the height of the roadway. Brace-rods 24, provided with turnbuckles 25, are fastened diagonally in the

middle span of each truss. Lateral stay-rods (not shown) provided with turnbuckles are extended diagonally under the joists and engage by their respective extremities with a 55 corresponding lug 13 on the impost and yoke 16 or the floor-beam. Guard-rails 26 are each secured at one end to a springer-beam and supported at the other end by a post 27, that 60 is secured by set-screw 28 in socket 14, formed on the impost. Said guard-rails and supporting-posts are preferably formed of gas-pipe.

By reference to Figs. 4 and 5 the springer and key beams are shown to each consist of 65 a single section of tubing or large gas-pipe. In each end of the key-beams is inserted a metal head 31, that forms a member of the hinge or angle of the arch. Said head is formed with an abrupt shoulder 32, that contains an 70 annular groove 33 for the reception of the extremity of the hollow beam. The portion 34 that extends beyond the beam is formed square in cross-section, with a transverse bolt-hole 35 for the insertion of a bolt to secure 75 one end of the brace-rods 24. Said head terminates in a transverse concave seat 36, with middle groove 37 to correspond in form and dimensions with seats 9 in the imposts.

In each end of the springer-beams is inserted in a similar manner head 38, formed with an abrupt shoulder 39 and annular groove 41. The projecting portion 42 is cylindrical in form and contains an axial bolt-hole 43. Annular rib 44 extends across the 85 middle portion of its convex face to register with groove 37 in the head of the key beam or groove 10 in the impost, as may be required.

In construction one end of the springer-beam is movably engaged with the corresponding impost by means of the convex face of the cylindrical head thereon being snugly seated in the concave seat in said impost and with the annular rib on the head registering with 90 the transverse groove in the seat to prevent lateral displacement of the beam. For the same purpose metal bars (not shown) may be bolted against each side of the joint thus formed by means of bolts inserted through 100 the bolt-holes 12 and 43 in the impost and in the head. In like manner the adjacent extremities of the springer and key beams may be properly engaged and the top of the posts

15 secured thereto by a bolt inserted through the axial bolt-hole 43 in the corresponding cylindrical head.

Having fully described my improvement, 5 what I claim as my invention, and desire to secure by Letters Patent, is—

1. In a bridge, tubular springer and key beams provided with metal heads to movably engage with the head in the adjacent beam 10 or with the impost as required.

2. In a bridge, the combination with a tubular key-beam terminating in heads containing transverse concave seats respectively and imposts formed with similar concave seats of 15 tubular springer-beams terminating in heads

containing transverse convex surfaces to movably engage with the adjacent seats in the key-beam and the impost respectively.

3. In a bridge, the combination with tubular springer and key beams the one terminating at each end in a transverse convex surface, the other in a transverse concave seat of a rib in the convex surface and a groove across the concave seat arranged to register the one with the other. 20

WILLIAM S. BRELSFOARD.
